(Cl. D47—7)

FIG-3

To all whom it may concern:

Be it known that I, Onesime H. Pons, a citizen of the United States of America, residing at Valdese, in the county of Burke, State of North Carolina, have invented a new, original, and ornamental Design for a Lady's Stocking, of which the following is a specification, reference being had to the accompanying drawings, forming a part thereof.

Fig. 1 is a front view of a lady's stocking showing my new design;

Fig. 2 is an enlarged view of an area of the shadow welt within the dotted area 2 in Figure 1.

Fig. 3 is an enlarged fragmentary view of the stocking shown in Fig. 1, depicting the decorative detail in the front of the shadow welt as it appears to the eye.

The rear welts, leg and foot portions are conventional.

I claim:

The ornamental design for a lady's stocking, substantially as shown and described.
